[57] **CLAIM**

The ornamental design for an electronic instructional housing, as described and shown.

DESCRIPTION

FIG. 1 is a top perspective view of the electronic instructional housing showing my new ornamental design thereof;

FIG. 2 is a front elevational view thereof;

FIG. 3 is a back elevational view thereof;

FIG. 4 is a top plan view thereof;

FIG. 5 is a bottom plan thereof;

FIG. 6 is a right side elevational view thereof; and,

FIG. 7 is a left side elevational view thereof.

Any numerals, letters or other indicia are shown for illustrative purposes only and do not comprise part of the claimed design. Any battery hatches, screws, bolts or other fasteners and/or electrical contacts are shown for illustrative purposes only and do not comprise part of the claimed design. The rectangular hatch in FIG. 7 is shown for illustrative purposes and does not comprise part of the claimed design.
